UNITED STATES PATENT OFFICE.

WILLIAM C. KRIEG AND JOSEPH T. ALBIN, OF DECATUR, ILLINOIS.

WASHING-MACHINE.

SPECIFICATION forming part of Letters Patent No. 298,890, dated February 19, 1884.

Application filed January 20, 1883. (No model.)

To all whom it may concern:

Be it known that we, WILLIAM C. KRIEG and JOSEPH T. ALBIN, residents of the city of Decatur, and State of Illinois, have invented 5 certain new and useful Improvements in Washing-Machines, of which the following is a full, clear, and exact description, such as will enable any one skilled in the art to which it relates to make and operate the same.

10 Our invention relates to that class of washing-machines in which the article to be washed is laid on a series of rollers and manipulated by a device attached to levers, one end of which is held by the operator, and the other supported by a swinging frame.

15 Our invention consists in a bracket of peculiar conformation, that connects and co-operates with a rubbing-board and a swinging frame, in a manner to be hereinafter set forth.

20 In the drawings accompanying and forming a part of this specification, Figure 1 is a transverse vertical section of a washing-machine embodying our devices. Fig. 2 is a front view of the lug used to connect the rubbing-board 25 with the levers. Fig. 3 is a section of Fig. 2 on dotted line *x x*. Fig. 4 is an end of one side of the roller-frame. Fig. 5 is section of Fig. 4 on dotted line *y y*. Fig. 6 is a plan of 30 an end of the box, showing the combined brace and handle. Fig. 7 is a bottom view of the rubbing-board, and Fig. 8 is a section of the same on dotted line *z z*.

35 *a* is the box. *b* are rollers supported by frame *b'*. *c* is the bracket that connects the rubbing-board with the levers. *d* is the rubbing-board, provided with concavities *d'*. *e* is the lever, with its fulcrum in hanger *f*. *g* is an upright attached to the box, and from which hanger *f* is suspended. *h* is a combined soap-40 shelf and rubbing-board support. *i* are combined braces and handles. *k* *k* are the legs of the box. *m* are cross-pieces that connect the sides of the roller-frame. Bracket *c* is constructed to fit over a projection on lever *e*, as 45 is indicated by dotted lines in Fig. 2. *c'* is a convex shoulder that rocks on the rubbing-board, and *c''* is the point to which the rubbing-board is attached. *b'* is provided with a dovetail slot, through which cross-piece *m* 50 passes. *m* is formed to fit the slot in *b'*, and is secured by wedge *n*. *i* extends entirely across

the end of the box, as shown, and is secured to both box and legs, thereby forming a handle for moving the machine, and a brace to prevent the box from spreading. The dovetail box in bracket *c* fits over the projection of the lever, making a secure connection, and the convex shoulder *c'* limits the rotary motion of the rubbing-board.

55 The construction of the roller-bed, besides insuring security, enables us to dispense with nails or screws, thereby lessening the danger of damage from rust. The box *a* is provided with a suitable lid, and the sides of the roller-bed *b'* and bracket *c* are made of metal and 60 galvanized or otherwise protected from rust.

65 In operation, the bed is properly supplied with water, and the article to be washed placed on the rollers under the rubbing-board. The rubbing-board may then be moved back 70 and forth over the rollers in the customary manner, and may also be given a reciprocating vertical motion, which, owing to the peculiar formation of said board, is of great utility. In the reciprocating vertical motion, the concavities *d'* become filled with air, which is 75 forced through the fabric, thereby removing the dirt without rubbing, and so making it possible to cleanse the most delicate fabric without risk of damaging the same.

80 When using the box for rinsing or similar purposes, the rubbing-board may be placed on support *h*, as shown in dotted lines in Fig. 1, and the roller-bed removed from the box.

85 The reciprocating vertical motion of the rubbing-board, by means of which air is forced through the fabric, is very useful in washing cloth of any thickness, and is peculiarly adapted to cleansing delicate articles.

Having thus described our invention, we 90 claim—

The bracket *c*, provided with the rounded portion *c'* and projections *c''*, in combination with an operative lever-frame attached to the bracket, as described, and the rubber *d*, pivoted to the projections *c''*, as and for the purposes set forth.

WILLIAM C. KRIEG.
JOSEPH T. ALBIN.
